ARRANGEMENT FOR DIRECTIONAL RECEIVING

Application filed June 5, 1924, Serial No. 717,914, and in Germany June 13, 1923.

My invention relates to radio apparatus and more particularly to arrangements for directional receiving, comprising generally a directional aerial and a non-directional aerial. An object of the invention is to produce such an arrangement that will give the usual cardioid characteristic and that will be able to receive a plurality of different wave lengths with the same adjustment of the apparatus as to phase relation between the currents in the directional and non-directional aerials.

Other objects will be apparent from the following specification and claims when considered with the accompanying drawing, in which:

The single figure is a circuit embodying the invention.

One of the best known connections for directional receiving is the combination of two receiving systems, one of them being a closed frame aerial or a system of frame aerials and the other an open aerial. The currents of these two receiving systems act upon a third circuit in such a way that the amplitudes of these currents produced by the two receiving systems are equal to one another and that the phases are 0° or 180° different from one another. The receiving characteristic of the frame aerial, as is well-known, depends on the cosine of the angle of the incoming waves, but the open aerial receives equally well from all directions. The resulting receiving characteristic of the combination of both systems is the well-known cardioid.

Such receiving arrangements are successfully used for eliminating atmospherics, as it has been found that atmospherics at most places come from certain directions. The atmospherics coming from a certain direction can easily be eliminated as the equal natural oscillations of both receiving systems caused by the same atmospheric can be completely compensated if both aerial systems have the same damping.

Aerial combinations of the above described kind are chiefly used for eliminating disturbances caused by undamped wave transmitters which do not lie in the same direc-

tion as the transmitting station to be received. Up till now an aperiodic frame aerial has been frequently combined with an open aerial for obtaining a cardioid shaped receiving characteristic.

In order to be able to adjust the right phase difference between open aerial current and frame aerial current, it was always necessary that either the open aerial itself or the circuit coupled to this open aerial could be tuned. Consequently the adjustment of the desired receiving characteristic is effective only for one certain wave-length.

The present invention relates to a method by which the effect of the open aerial can be nearly aperiodically transferred to the common receiving circuit. The required phase of the current caused by the open aerial can be adjusted without syntonization. The principle of the invention is fully explained by the drawing. K is the entrance circuit of the radio frequency amplifier of the receiving apparatus, which is supplied by the effect of the open aerial and the effect of the frame aerial having a phase displacement of 0° or 180° respectively. D is the frame aerial coil connected to the entrance circuit K. The energy induced in the open aerial circuit F is led to the input circuit of thermionic tube E₁ by means of coupling coils A.

In the usual former arrangements the effect of the open aerial was led to a syntonizing circuit by which the effect of the aerial current was transferred in right phase to the entrance circuit K of the radio frequency amplifier. As shown in the drawing another arrangement is used according to the invention for adjusting the phase. The energy acquired by the open aerial is led to the grid circuit of a vacuum tube E₁, the plate-filament circuit of which contains a self-inductance L₁ and a resistance L₂ serially connected. The voltage drop which can be taken from this inductance and resistance has a phase relation to the plate-filament current of the vacuum tube and consequently with the aerial current acting on the grid of this vacuum tube according to the points across which the voltage drop is taken. If only the voltage drop across the resistance is used, it has the same phase as

the alternating current component of the plate-filament current. If only the voltage drop across the self-inductance is used, its phase is 90° different from that of the current. 5 Consequently any phase between 0° and 90° can be obtained by choosing the branching points 1 and 2 in such a way that a part of the inductance coil L_1 as well as a part of the resistance L_2 lies between them. This voltage is 10 now led to the grid of another vacuum tube E_2 , the plate-filament circuit of which acts directly by means of coupling coils B upon the entrance circuit of the radio frequency amplifier. By means of this adjustment of 15 the phase a receiving characteristic is obtained which remains the same for a larger wave-scale. Of course this adjustment of phase according to the present method is not quite independent of the frequency as the 20 voltage across the inductance coil comprises this frequency. The adjustment of the phase can remain unaltered for the wave $\lambda \pm \Delta\lambda$, if $\Delta\lambda$ is equal to 5-10% of λ , in order to obtain the same direction finding characteristic of 25 the arrangements. It is absolutely necessary to employ a coupling between two vacuum tubes in the present invention as the above-mentioned resistance L_2 used for the regulation of the phase must be very high. Such 30 a high resistance can be inserted into the plate filament circuit of a vacuum tube because of the high internal resistance of this vacuum tube, but it would be practically impossible to use such a high resistance in a circuit which 35 contains no vacuum tube. The different phase relations are shortly explained by the following:

If R_i is the internal resistance of the vacuum tube and E_g the grid voltage, the phase 40 angle C of the alternating current I_a in the plate-filament circuit is given by:

$$\tan C = \frac{\omega L_1}{R_i + L_2}$$

45 where ω is equal to 2π times the frequency.

If L_1 is small in comparison with R_i and L_2 , I_a is approximately in phase with E_g . Designating those parts of L_2 and L_1 which lie between the branching points 1 and 2 as l_2 and 50 l_1 , then the phase ψ of the used voltage in comparison with I_a is given by:

$$\tan \psi = \frac{\omega l_1}{L_2}$$

55 If l_1 is large in comparison with L_2 , the change in phase angle C with change in frequency is less than proportional to the change in ω since the tangent of an angle rises more rapidly than the angle, especially for angles 60 just under 90° in value. On the contrary, in the former method in which the phase was adjusted by means of a tuned circuit, a phase alteration from nearly $+90^\circ$ to nearly -90° would have resulted by the alteration of λ by 65 merely $\pm 5\%$.

The resistance L_2 appropriately consists of a vacuum tube the apparent resistance of which (plate-filament) can be regulated by altering the voltage applied to the grid.

This method slightly differs from former methods in so far as the phase angle is also altered by an alteration of L_2 , but this circumstance is of no importance in practice because the amount of change from this cause is negligible. 75

Having described a single embodiment of my invention, I am entitled to all modifications thereof as fairly fall within the scope of the claims herewith.

Having described my invention, I claim: 80

1. In combination, a directional antenna, an aperiodic non-directional antenna, means for coupling said antennæ comprising circuits respectively coupled to each antenna and a resistance and impedance in series 85 common to said circuits.

2. In combination, a tuned directional antenna and an aperiodic non-directional antenna, means for coupling said antennæ, comprising a circuit coupled to the directional antenna and a radio frequency amplifier coupled to the non-directional antenna, said amplifier having a resistance in its output common to the circuit coupled to the directional antenna. 90

3. In combination, a directional antenna and an aperiodic non-directional antenna, means for coupling said antennæ comprising a circuit coupled to the directional antenna and a radio frequency amplifier coupled to the non-directional antenna, said amplifier having a reactance and a resistance in its output common to the circuit coupled to the directional antenna. 100

4. In combination, a tuned directional and 105 an aperiodic non-directional antennæ, means for coupling said antennæ comprising a circuit coupled to the directional antenna and a radio frequency amplifier coupled to the non-directional antenna, said amplifier having a reactance and a resistance in its output 110 common to the circuit coupled to the directional antenna, means adjustably associated with said reactance for regulating phase relation between said antennæ. 115

5. In combination, a tuned directional and an aperiodic non-directional antenna, an amplifier, having grid and plate circuits, coupled to one antenna, reactances in the plate circuit, a second amplifier adjustably 120 associated with said reactances whereby output phase relation may be varied with respect to remaining circuits.

6. In combination, a tuned directional and an aperiodic non-directional antenna, an amplifier, having grid and plate circuits, coupled to one antenna, reactances in the plate circuit, a second amplifier having an output circuit coupled to another antenna, 125 adjustably associated with said reactances, 130

whereby output phase relation may be varied with respect to remaining circuits.

6 7. In combination, a tuned directional and an aperiodic non-directional antenna, an amplifier, having grid and plate circuits, coupled to one antenna, reactances in the plate circuit, a second amplifier having an output circuit coupled to another antenna, adjustably associated with said reactances, 10 whereby output phase relation may be varied with respect to remaining circuits, and a single tuning element for said directional antenna circuit.

15 8. In combination, directional and non-directional antennæ, a single tuning element associated with one of said antennæ, and a pair of coupling circuits between the antennæ having a phase shifting means common to said circuits.

20 9. In a receiving device a tuned directional and an aperiodic non-directional antenna, means to lead the energy acquired by the said non-directional antenna to the grid circuit of a vacuum tube the plate circuit of which 25 contains a self inductance in series with a resistance whereby a phase difference may exist between the voltage drop across said inductance and resistance and the plate current of said vacuum tube and consequently with a 30 non-directional antenna current, means comprising the grid circuit of a second vacuum tube circuit inductively coupled to the circuit of said directional antenna and a radio frequency amplifier for leading said voltage to 35 said directional antenna circuit.

40 10. In combination a tuned directional antenna circuit, an aperiodic non-directional antenna circuit, two vacuum tube circuits and a receiving circuit, said last named circuit being coupled directly to said directional antenna circuit, inductive means for leading energy from said non-directional antenna circuit to the input side of one of said vacuum tube circuits, a resistance in series with a self 45 inductance in the output side of said vacuum tube circuit and means in the input side of the other vacuum tube circuit comprising an adjustable connection to said self inductance and resistance for connecting the output side 50 of the first named vacuum tube circuit to the input side of the second named vacuum tube circuit whereby the phase difference between the input sides of both of said circuits may be adjusted as desired.

ALF HERZOG.
